(57) **CLAIM**

The ornamental design for a square, as shown and described.

DESCRIPTION

FIG. 1 is a perspective view of a square.

FIG. 2 is right side view of the square shown in FIG. 1.

FIG. 3 is a left side view of the square shown in FIG. 1.

FIG. 4 is a front side view of the square shown in FIG. 1.

FIG. 5 is a rear view of the square shown in FIG. 1.

FIG. 6 is a top view of the square shown in FIG. 1.

FIG. 7 is a bottom view of the square shown in FIG. 1.

FIG. 8 is a perspective view of the square according to an alternate embodiment of the invention.

FIG. 9 is a right side view of the square shown in FIG. 8.

FIG. 10 is a left side view of the square shown in FIG. 8.

FIG. 11 is a front side view of the square shown in FIG. 8.

FIG. 12 is a rear view of the square shown in FIG. 8.

FIG. 13 is a top view of the square shown in FIG. 8; and,

FIG. 14 is a bottom view of the square shown in FIG. 8.

The present application is directed to the shape and contour of the design illustrated in the drawings. The broken line showing of the environment is for illustrative purposes only and forms no part of the claimed design. The broken lines which define the boundaries of the claimed design form no part thereof.
